UNITED STATES PATENT OFFICE.

MAYO E. ROE, OF ELYRIA, OHIO, ASSIGNOR TO THE COLSON COMPANY, OF ELYRIA, OHIO, A CORPORATION OF OHIO.

INVALID CHAIR AND THE LIKE.

Application filed May 8, 1926. Serial No. 107,629.

My invention relates to an improved bumper for vehicles and more particularly to a bumper adaptable for use on such vehicles as wheeled invalid chairs.

5 An object of my invention is to provide an improved bumper which may be easily and quickly attached or detached to or from a vehicle such as a wheeled invalid chair.

Another object of my invention is to provide 10 a bumper which will not only protect the vehicle carrying it, but will also protect against injury articles against which the bumper may contact, even when the contact is had with considerable force.

15 Another object of my invention is to provide a bumper for an invalid chair which will guard the hands of the occupant from injury should the chair be propelled against an extraneous object.

20 Another object of my invention is to so construct a bumper that it may comprise but few parts, durable in construction, inexpensive to manufacture, and assemble.

Other objects of my invention and the invention itself will be apparent by reference 25 to the following description of an embodiment of my invention, and in which description reference will be had to the accompanying drawings, forming a part of this specification.

30 Referring to the drawings:

Fig. 1 shows a front elevational view of an invalid chair with an embodiment of my invention applied thereto;

35 Fig. 2 shows a side elevational view of the embodiment of my invention as shown in Fig. 1;

Fig. 3 shows a top plan view of the embodiment of the foregoing figures, certain 40 vehicular parts being omitted in this view;

Fig. 4 shows a rear elevational view thereof; and

Fig. 5 shows a perspective view of a fragment 45 of the rubber strip, core and fastening means enlarged.

Referring to all the figures of the drawings, in all of which like parts are designated by like reference characters, 1 generally designates an invalid chair provided 50 with a back 3, adapted to be inclined rearwardly from the position in Figs. 1 and 2 to various positions approaching a horizontal position by virtue of the pairs of hinges 36, 62, 60 and 48. A sector 38 and ratchet 55 detent 39, releasably engageable therewith,

are adapted to hold the back in any desired inclined position.

At 2, I show a chair seat, spring mounted on the chair frame 28, a plurality of helical springs 14, secured at their upper ends to the seat and at their lower ends to a skeleton platform comprising a pair of strips 15, which are each supported at their front and rear ends by a pair of angle iron posts 17. The posts 17 are mounted rigidly upon the chassis frame side bars 16, and reenforcing truss bars 24 extend diagonally between the ends of the strips 15 and the chassis side bars 16, to which they are rigidly secured, the various parts comprising the chassis frame and spring carrying platform assembled by means of securing rivets or by welding, or in any other well known way.

At 7 and 8, I provide a pair of leg rests comprising foot boards 9 and 10, respectively, hinged to the longitudinally extending portions 7 and 8 at 49. The hinging bracket 49 interconnecting the foot rests 9 and 10 and the leg rests 7 and 8, comprise ratchet retaining means for holding the foot rests 9 and 10 in any desired angular position, relative to that of the leg rests 7 and 8, from a position wherein the foot rests extend at right angles thereto, to a position wherein the foot rests extend longitudinally from the leg rests. This mechanism, although it may take various forms, may comprise a ratchet sector carried by the one hinged part and a spring pressed ratchet pawl engageable therewith and adapted to enter any desired one of the notches in the sector. This mechanism being no part of the present invention, is not specifically illustrated.

The leg rests 7 and 8 are hinged at their upper ends at 42 and 43, each to a one of a pair of leg rest supporting boards 6 and 11, which are telescopic under the seat 2, being retained in telescoping position therewith by a pair of metallic strips 88 and 89 which are bolted to the under side of the seat and extend transversely thereof, the first under the extreme forward portion of the seat and the second being spaced upwardly therefrom, each containing downwardly extending loops 44 and 45 adapted to act as trackways for the sliding telescopic boards 6 and 11. This arrangement permits the extension of the leg rests 7 and 8 to any desired position forwardly of the seat 2 and, together with the hinging of the leg rests at 110

the point 43 with the boards when the leg rests and foot boards are in extended position, forms with the boards, the seat 2 and back 3, a reclining couch.

5 Pivoted at 4, to the sides of the seat and adjacent the forward ends thereof, are a pair of vertical disposed posts 32 and 33, which are adapted to support the forward ends of the arm rests 34 and 35. The arm rests 34 and 35 are supported by longitudinally extending metallic bars 61 having rear depending portions which are perforated to admit a hinge pin 40, which swivelably connects the back to the arms. To a depending 10 portion 63 of the member 61, each sector 38 is pivotally secured, each of the sectors having notches on its under side adapted to engage with a detent 39 carried on a metallic strip 64, secured to the side of the chair 15 back. The strips 64 and bars 61 are pivoted together at 36 to permit various angular adjustments of the back by adjustment of the sector 38 and detent 39.

The leg rests and foot rests may be adjusted vertically by virtue of the tooth sector 65 pivoted to the leg rests at 66 and supported at the rear by cords 67 and 68 which are supported on the arm rests at 69 and 70. The teeth of the sectors are adapted to engage depending ratchets 71 and 72 supported by the horizontal bars 6 and 11 and adapted to slide horizontally when the leg rests are horizontally adjusted and adapted to retain the teeth of the sector to support the leg rests in any of their vertical adjusted positions.

Depending from the forward end of the frame 16 are a pair of anti-tilting devices 90 and 100.

40 The frame and chair heretofore described are supported by a pair of large wheels 50 and 51 carried on the axle 26 supported in the forward end of the frame in suitable journals or bearings.

45 To the vehicle as above described, I apply a bumper comprising a metallic support 20, preferably made of channel iron, and a facing 21 of rubber, the rubber facing having a rectangular bore 41 and the iron support 50 presenting a groove 19 on its outer surface. The rubber facing is rounded on its exterior surface, as illustrated at 92, and has an inwardly extending extension 18, of such a size and form as to be capable of being wedged 55 tightly within the outer groove 19 of the channel iron.

Prior to application of the rubber facing 21 to the channel iron, a strip of steel 102, preferably cold rolled steel, is inserted 60 through the bore 41, being preferably of such a size as to fit the bore. In Fig. 5, wherein a fragment of the rubber facing with the metallic strip core in place therein is shown, I show, subsequent to the insertion 65 of the strip within the rubber, a metallic pin

93 through an opening 94 in the steel strip, the pin being insertable through a hole 95 extending from the rounded outer face 92 of the rubber to the opening 94 in the steel strip, the pin being insertable through a hole 95 extending from the rounded outer face 92 of the rubber to the opening 94 in the strip and aligned therewith, there being a plurality of holes 95 through the rubber and openings 94 in the steel strip provided at intervals throughout the composite facing element. Prior to insertion of the composite facing to the channel iron 20, I insert pins, such as the pin 93, through the different aligned openings 95—94 and project them through the inward extension 18 of the rubber.

The composite facing, having the rubber exterior and the steel strip interior, is then applied with its projection 18 pressed into the groove 19 of the channel iron, and the pins 93 will have their ends projected through openings provided for the purpose extending through the channel iron 20. The securing of the composite facing, having a rubber exterior, to the channel iron is then effected by riveting over the ends of the metallic pins 93 which project through the channel iron. Up to this point in the operation of forming my improved bumper element, the channel iron and facing are presumed to be substantially straight, but after the riveting of the facing to the channel iron the same will be bent into the shape illustrated best in Fig. 3, wherein a bend 13 is given to the bumper at one end adjacent the rear of the large wheels 50 and 51, and another bend is imparted to it at the point 84 adjacent the front ends of the large wheels.

At 96, the composite bumper, comprising channel iron and rubber facing with metallic core, is given a reverse re-entrant bend to form a hook end 23, and which hook end is adapted to embrace the caster head 22, each of the two such heads being rigidly carried at a forward corner of the chassis frame. The chassis frame comprises, as has been noted, the frame side bar element 16 and front axle 26, and comprises a transverse bar 98 rigidly joining together the forward ends of the frame side bar elements 16. At 25, I show a loop projecting from the inner face of the channel iron 20, to which it is riveted or otherwise secured at 85 and which loop has an upwardly extending portion perforated at 12 to admit the ends of the rear axle 26 which projects through the perforations. Securing nuts 99 are provided at the axle ends and serve not only to rigidly support the bumper on the axle ends but retaining the wheels 50 and 51 on the axles together with the hand rails 30 and 31, which are secured to the wheels and rotate with them.

The rubber facing may be omitted at the re-entrant ends of the bumper 23 for the sake of economy in rubber, since no function would be performed by rubber facing inwardly disposed, as at 23.

A pair of hand grips 30 and 31 for propelling the chair by the occupant are secured to spokes 87 of the wheels 50 and 51, and project laterally a short distance from the side of each wheel. The rear of the chair is supported by a pair of trailer caster wheels 53 and 54 journaled in stub forks 52, which swivel in vertically disposed bearing housings 22 secured to the rear of the frame.

16. The chair frame, anti-tilting bracket and associated parts, heretofore referred to, are more fully described in my co-pending application and form the subject matter thereof, 20 entitled Invalid chairs, Serial No. 108,499, filed May 12, 1926, only a general description thereof being herein given to facilitate a ready understanding of the present invention.

25. The bumper extends forwardly along the side of the chair and substantially horizontal with the supporting surface for the chair, to a point adjacent the forward end of the wheel treads 27 of the large forward wheels 30 of the chair. The forward end of the bumper is curved inwardly at 13, and is also bent inwardly at 84 so that the hand grips and wheels are partly surrounded by the bumper. The bracket 25 is bent at 97 so 35 as to space the bumper from the wheel treads and the hand grips.

A bumper applied to an invalid chair in the manner set forth in the foregoing will project laterally of all parts of the chair and prevent contact of any metallic or hard 40 parts thereof with other objects. The rubber facing of the bumper will strike against the objects and absorb any shock resulting therefrom.

45. It will be noted that the caster wheels 53 and 54, upon rearward movements of the vehicle, will swivel about its head 22, and that the portion 73 of the wheel will then take an advance position relative to the direction of movement of the vehicle but that at such advanced position it will be disposed rearwardly in the line of motion with respect to the entire curved end 96 of the bumper. In this way, it will but infrequently happen that the caster wheel 53 55 will come into contact with extraneous objects, and all of the wheels preferably having rubber tires and the bumper being faced with rubber, at all times the vehicle is prevented from the likelihood of having any but rubber faced portions coming in contact with extraneous objects.

Having thus described my invention in a single embodiment, I am aware that numerous and extensive departures may be made

from the embodiment herein illustrated and described but without departing from the spirit and scope of the invention.

I claim:

1. In an invalid chair, the combination 70 with a pair of large propelling wheels, one of said wheels comprising an axle portion, a caster wheel and a bumper secured to the vehicle at one end adjacent the caster wheel and extending along a lateral outer side of the said one of the propelling wheels, said bumper being supported near its other end by the said wheel axle.

2. In an invalid chair, the combination 80 with a pair of large propelling wheels, one of said wheels comprising an axle portion, a caster wheel and a bumper secured to the vehicle at one end adjacent the caster wheel and extending along a lateral outer side of the said one of the propelling wheels, said bumper being supported near its other end by the said wheel axle, said bumper comprising an outer rubber cushion facing and an inner support. 85

3. In an invalid chair, the combination 90 with a pair of large propelling wheels, one of said wheels comprising an axle portion, a caster wheel and a bumper secured to the vehicle at one end adjacent the caster wheel and extending along a lateral outer side of the said one of the propelling wheels, said bumper being supported near its other end by the said wheel axle, said bumper comprising an outer rubber cushion facing and an inner support of channel iron, said facing being secured to the channel iron by a plurality of pins passing through openings provided in the channel iron and into the interior of the facing, and supporting means at the ends of the pins on the interior of the 100 facing embedded in the material thereof. 105

4. A bumper for invalid chairs comprising a metallic support provided with a channel and spaced apertures, a strip of pliable material having a longitudinal rib formed thereon and a bore, both extending throughout its length, spaced openings provided in the strip aligning with the spaced apertures in the metallic support, a reinforcing bar telescoped into the bore, having apertures 110 alignable with its apertures in said metallic support, and said strip and rivets passing through said apertures and riveted to the metallic support. 115

5. In a vehicle, the combination with forward and rear supporting wheels therefor, an axle for one of said wheels, a bumper for the vehicle, said bumper extending along a lateral side of the vehicle and having its forward portion secured to the axle. 120

6. In a vehicle, the combination with forward and rear supporting wheels therefor, an axle for one of said wheels, a bumper for the vehicle, a forward portion of said bumper secured adjacent the axle and ex- 125 130

tending rearwardly along a lateral side of a forward and a rearward wheel of the vehicle.

7. In a vehicle, the combination with forward and rear supporting wheels therefor, an axle for one of said wheels, a bumper for the vehicle, a forward portion of said bumper rigidly secured adjacent the axle and extending rearwardly along a lateral side of a forward and a rearward wheel of the vehicle.

8. In a vehicle, the combination with forward and rear supporting wheels therefor, an axle for one of said wheels, a bumper for the vehicle, a forward portion of said bumper secured adjacent the axle and extending rearwardly along a lateral side of a forward and a rearward wheel of the vehicle and secured at its rear portion adjacent the rear of the frame of the vehicle.

9. In a vehicle, the combination with forward and rear supporting wheels therefor, an axle for one of said wheels, a bumper for the vehicle, said bumper extending along a lateral side of the vehicle and having its forward portion secured to the axle, said bumper bent inwardly at one of its ends. 25

10. In a vehicle, the combination with forward and rear supporting wheels therefor, an axle for one of said wheels, a bumper for the vehicle, a bracket secured to the bumper intermediate the ends thereof, said bracket being secured to the axle and adapted to support the bumper along a lateral side 30 of the vehicle. 35

In testimony whereof I hereunto affix my signature this 2nd day of April, 1926.

MAYO E. ROE.
